UNITED STATES PATENT OFFICE.

MAGNUS GROSS, OF NEW YORK, N. Y.

STEAM-SUPERHEATER.

SPECIFICATION forming part of Letters Patent No. 284,958, dated September 11, 1883.

Application filed February 23, 1883. (No model.)

To all whom it may concern:

Be it known that I, MAGNUS GROSS, of the city, county, and State of New York, have invented a new and useful Improvement in 5 Steam-Superheaters, of which the following is a full, clear, and exact description.

Reference is to be had to the accompanying drawings, forming a part of this specification, in which similar letters of reference indicate 10 corresponding parts in all the figures.

Figure 1 is a sectional side elevation of the superheater. Fig. 2 is a sectional end elevation of the same. Fig. 3 is a longitudinal sectional view of the furnace and superheater, 15 showing their relation to each other; and Fig. 4 is a cross-section of the same.

Whenever steam is used for the purpose of decomposition, and the combination of its elements—hydrogen and oxygen—with other gaseous bodies, or in the manufacture of water-gas, the great hindrance to any such operation lies in the fact that the steam, in passing through retorts, generators, or other apparatus constructed for such purposes, quickly 25 lowers the heat required for the safe conduction of such processes, rendering them intermittent and unreliable, instead of constant and uniform, as they ought to be.

In connection with the apparatus and process for making gas from naphtha or other liquid hydrocarbons described in Letters Patent No. 206,724, granted to me August 6, 1878, and for the purpose of rendering the said process more perfect, I have devised a superheater 30 which meets the requirements and avoids the difficulties hereinbefore mentioned as attending the use of superheated steam.

In the manufacture of gas, in every bench A, which should have not less than four and 40 may contain as many as nine generating or distilling retorts B, is inserted an additional retort, C, for the purpose of housing the superheater. The forward part of the retort C rests upon a double wall, D E, and never becomes very hot. The rear part of the retort 45 C rests upon the rear wall, F, of the bench, and upon a partition-wall, G, placed at a little distance from the rear wall, F, and forming a chamber through which the products of 50 combustion are to pass from the main or furnace chamber B' to the chimney, and with which the interior of the retort C communicates by means of an opening, H, so that all rarefied and highly-heated air, spent fire-gases, or vapors in the superheating-retort C

pass into the hot-air chamber, and thence to the chimney. By this construction an even and uniform tension is maintained in the superheater, and at the same time the possibility of a vacuum is avoided. On the bottom 60 of the retort C are placed four or five rows of pieces, I, of chamotte or fire-brick, at equal distances apart, and which are covered and the spaces between them are filled to the depth of several inches with pulverized fire-clay J, 65 the object being to provide a shield to protect the superheating-pipes from contact with the bottom of the retort. The retort is now ready to receive the superheater proper, which is constructed as follows: From twelve to fifteen 70 lengths of wrought-iron pipe, K, of double or triple the ordinary thickness, forming, when connected, a length of not less than one hundred feet, are connected at their ends by return-bends L, and the connected pipe is 75 provided at one end with an inlet-pipe, M, and at the other end with an outlet-pipe, N, which inlet and outlet pipes M N are only one-third the diameter of the superheating-pipe K. 80

The parts of the superheater that are to be subjected to incandescence are wrapped in sheets Z of asbestos paper, coated inside and outside with plumbago and clay paste, and secured in place by strong wire a. 85

The return-bends L at the ends of the pipes K never become red-hot, and are thus not liable to be injured.

The ends of the retort C are closed by flat cast or wrought iron covers R, which are perforated, one for the passage of the inlet-pipe M, and the other for the passage of the outlet-pipe N. 90

Having thus fully described my invention, I claim as new and desire to secure by Letters 95 Patent—

1. The combination of the superheating-pipes K, the covering Z, secured around said pipes collectively, and the retort C, having the shield of fire-brick I and fire-clay J in its bottom, substantially as shown and described. 100

2. In a steam-superheater, the combination, with the retort C and the pipes K, of the pieces I of fire-brick and the pulverized fire-clay J, substantially as herein shown and described, whereby the superheating-pipes are kept out of contact with the retort, as set forth. 105

Witnesses: MAGNUS GROSS.
